UNITED STATES PATENT OFFICE.

WILLIAM W. HAZLETT, OF TORONTO, OHIO.

FIRE-PROOF FLOOR.

SPECIFICATION forming part of Letters Patent No. 326,735, dated September 22, 1885.

Application filed June 13, 1885. (No model.)

To all whom it may concern:

Be it known that I, WILLIAM W. HAZLETT, of Toronto, in the county of Jefferson and State of Ohio, have invented certain new and 5 useful improvements in Fire-Proof Floors, of which the following is a full, clear, and exact description.

My invention relates to fire-proof floors, and especially to a protection for the lower portions of the flanged iron beams of the floors, and has for its object to improve the construction of the floors by providing a better protection to the beams, and also to facilitate the setting of the tile arches between the beams.

15 The invention consists in certain novel constructions and combinations of parts of the beam protection, and its arrangement with the beams and the arch-tile of the floor, all as hereinafter fully described and claimed.

20 Reference is to be had to the accompanying drawings, forming part of this specification, in which similar letters of reference indicate corresponding parts in both the figures.

Figure 1 is a perspective view of a portion 25 of a fire-proof floor embodying my improved system of protection to the iron beams; and Fig. 2 is an end view of one of the floor beams, the protecting-tiles at its lower edge, and the skew-back tiles at each side of the beam.

30 The letter A indicates the iron I-beams. B are the skew - back tiles, laid next to and at opposite sides of the beams. C are the intermediate tiles, and D indicates the key - tile, the hollow tiles B C D together forming a flat 35 arch between the beams A A, as shown in Fig. 1. Cement may be filled in over the tiles and level with the tops of the beams.

The letters E E indicate cover plates or 40 tiles made of refractory material, and placed directly on the opposite lower flanges, *a a*, of the beams A, each tile E being formed with an upper portion, *e*, which rests on the flange *a* of the beam, and a side portion, *e'*, which extends below the beam. The inner faces of 45 the pendent portions *e' e'* of the flange - cover tiles E E of each beam A are inclined downward toward each other, as at *e'*, so as to form between them and the beam a dovetail-shaped recess, in which is placed the tile F, which is 50 beveled at the edges to fit the inclined faces *e'* of tiles E E, so as to be supported by said

tiles at the lower edge or face of the beam. I make the tiles F concaved on their upper faces to form air-spaces *f* between the bodies of said tiles and the beams A, to give better protection 55 to the beams from flames or heat below them than if these lower tiles laid flat against the beams. The skew-back tiles B are recessed at and along their lower outer portions to fit over the upper parts, *e*, and at the pendent side portions, 60 *e'*, of the flange - protection tiles E, and the tiles B have inturned lip-positions *b*, which fit below the undercut outer faces, *e''*, of the flange-cover tile E, to lock the latter in place. The faces of all the tiles B C D E F, where 65 they join with each other, are corrugated, scratched, or roughened to give a better hold to the cement used in the joints, and the exposed lower faces of the tiles will also be roughened or corrugated to give a better hold 70 to the plaster finish.

It is evident that the beam-protection tiles E F may be fixed to the beams, and will hold their places on the beam flanges *a a* by interlocking with each other, as above explained; 75 hence these tiles E F may be put in place before the main tiles B C D of the floor-arch are set, which facilitates the setting of the arch-tiles between the beams, and has advantages in this respect over a tile protection at the 80 lower beam - flanges, which will not keep its place except as held to the flanges by the skew-back tiles, as the hollow-tile arches are set between the beams.

I am aware that ceilings have been constructed of I-iron beams having tiles provided with dovetailed recesses slid on the lower flanges of said irons. Skew-back tiles rested on said lower flanges and tiles, and intermediate inclined tiles, a keystone - tile, and cement were used to complete the ceiling; also, 85 that these tiles have been provided with roughened or corrugated surfaces; also, that the tile for the lower flange of the iron has been formed in two sections having their inner sides recessed to receive the flange, and roughened on their under surfaces to better hold the plastering, and I do not claim such as of my invention. 95

Having thus described my invention, what 100 I claim as new, and desire to secure by Letters Patent, is—

1. A protection for the lower parts of the iron beams of fire-proof floors, comprising opposite tiles E E, having upper parts, *e*, over the beam flanges, and pendent side portions, *e'*, and the tiles F, supported below the beam by the parts *e' e'* of opposite tiles E E, substantially as herein set forth.

2. A protection for the lower parts of the iron beams of fire-proof floors, comprising opposite tiles E E, having upper parts, *e*, over the beam-flanges, and pendent side portions, *e'*, and the tiles F, supported below the beam by the parts *e' e'* of opposite tiles E E, and said tiles F having concavities in their upper faces, forming an air-space, as at *f*, between them and the beam, substantially as herein set forth.

3. In fire-proof floors, the combination, with beams having lower flanges and tile arches set between the beams, of a beam-protection comprising flange-cover tiles E E, formed with upper parts, *e e*, pendent side parts, *e' e'*, and

tiles F, supported below the beams by parts *e' e'* of tiles E, substantially as herein set forth.

4. In fire-proof floors, the combination, with beams having lower flanges and tile arches set between the beams, of a beam-protection comprising flange-cover tiles E, formed with upper parts, *e*, pendent side parts *e'*, and tiles F, supported below the beams by parts *e'*, of tiles E, and said tiles F having concavitated upper faces forming an air-space, as at *f*, below the beams, substantially as herein set forth.

5. In fire-proof floors, the combination, with beams A A, having flanges *a a*, and the tile arch B C D, of the protection-tiles E E F and said arch-tiles B B, having lips *b* under the flange-cover tiles E E, substantially as herein set forth.

WILLIAM W. HAZLETT.
